UNITED STATES PATENT OFFICE.

WILLIAM S. McLEWEE, OF NEW YORK, N. Y.

HANGING LAMP.

SPECIFICATION forming part of Letters Patent No. 290,341, dated December 18, 1883.

Application filed May 10, 1883. (No model.)

To all whom it may concern:

Be it known that I, WILLIAM S. McLEWEE, of New York, in the county and State of New York, have invented a certain new and useful 5 Improvement in Hanging Lamps, of which the following is a specification.

The object of my improvement is to provide for raising and lowering a hanging lamp, and also to enable the reservoir and its appurtenances to be drawn down, so as to separate it from its shade or the draft-inducing devices to facilitate lighting the burner.

The improvement consists in the combination, with a lamp-reservoir and a shade or draft-inducing device, of cords, bands, or chains connected at one end with the reservoir or a holder, in which it is supported, and at the other end with the shade or draft-inducing device, pulleys over which these cords, bands, or chains pass, other cords, bands, or chains connected at one end with the said pulleys and at the other end to a weight, whereby the entire lamp is counterbalanced, and a hanger provided with pulleys over which the last said cords, bands, or chains pass.

In the accompanying drawings, Figure 1 is a side view of a lamp embodying my improvement, the parts being shown as adjusted for lighting the burner. Fig. 2 is a side view, partly in section, the parts being shown as adjusted into position for use; and Fig. 3 is a detail view, upon a larger scale, of one of the pulleys and the bearings provided for it in the hanger.

Similar letters of reference designate corresponding parts in all the figures.

A designates a reservoir for oil or other illuminating material. As here shown, it is provided with a burner, B, which may be of any of the well-known kinds for burning kerosene.

C designates a holder, which may be made of metal, and which receives and supports the reservoir A.

D designates a globe, shade, or shield, which may be made of glass, and at the top has an outwardly-projecting lip, S, fitting within a metal ring or crown, E, as shown in Fig. 2. This ring or crown is detachably secured in place by screws a, passing through the ring or crown and extending under the lip S.

Rods F extend from the holder C up into the globe, shade, or shield D; and G designates cords, bands, or chains, which at one end are fastened to these rods, and, extending thence over pulleys H, are at the other end fastened to the ring or crown E. The pulleys H are supported in frames or straps b. To these frames or straps b are attached cords, bands, or chains I, which extend over pulleys J in a hanger, K, and have attached to their depending ends a weight, L, of sufficient heft to counterbalance the lamp.

The entire lamp may be adjusted into different positions by lifting it or pulling it down as a whole, as the counterbalance-weight will maintain it in any position to which it may be adjusted. To prevent the consumption of the oil or preponderance of the weight of the portions of the cords, bands, or chains I on either side of the pulleys J from affecting the poise of the lamp, I may make the pulleys J turn with considerable friction, yet not too much to prevent the lamp from being adjusted by hand to different positions. I may for this purpose adopt the construction shown in Fig. 3. As there shown, the pulley J is keyed or otherwise secured fast to its shaft or axle J', and the latter has at one end a head, c, and at the other end nuts d d screwed upon it. The shafts or axles rotate in bearings e, formed in the hanger K, and by means of their nuts d d the pulley shafts or axles may be clamped in their bearings, so that their rotation will be more or less resisted or retarded by friction.

The globe, shade, or shield D and its ring or crown E are heavier than the lamp-reservoir and its appurtenances; hence they will more than counterbalance the reservoir and its appurtenances, and the globe, shade, or shield will normally rest on the reservoir or on an appurtenance thereof.

When the burner is to be lighted, the reservoir is pulled down, so as to separate it and the globe, shade, or shield.

What I claim as my invention, and desire to secure by Letters Patent, is—

In a lamp, the combination, with a reservoir and a shade or draft-inducing device, of cords, bands, or chains connected at one end with the reservoir or a holder in which it is sup-

ported, and at the other end with the shade or draft-inducing device, pulleys over which these cords, bands, or chains pass, other cords, bands, or chains connected at one end with the 5 said pulleys and at the other end to a weight, whereby the entire lamp is counterbalanced, and a hanger provided with pulleys, over which

the last said cords, bands, or chains pass, substantially as specified.

W. S. McLEWEE.
